UNITED STATES PATENT OFFICE

2,491,092

DROP WIRE COVER AND WARP BRUSH

John S. Denney, La Grange, Ga.

Application December 17, 1948, Serial No. 65,892

6 Claims. (Cl. 139—349)

1

This invention is particularly concerned with the preventing of trash of all kinds from falling on the drop wires or detectors forming part of a warp stop motion equipment of a loom. As is well-known in the art when lint or other trash on the warp is permitted to come into contact with the drop wires or detectors draw-backs, breakouts and other objectionable defects develop in the finished cloth.

The primary object of this invention is to provide simple, economical and effective means for preventing lint, cotton and other trash contacting the drop wires or detectors, with the result that loss due to defects in the cloth is reduced to a minimum and the production capacity of the loom is materially increased.

Briefly, the present invention consists in the provision of a combined drop wire or detector finger cover and warp brush for attachment to the loom to substantially enclose the drop wires and to wipe the warp clean to thereby preclude the possibility of lint and other trash on the warp passing therewith into contact with the drop wires or detector fingers.

The invention together with its objects and advantages will be best understood when the following detailed description is read with reference to the accompanying drawing in which is illustrated what is presently considered a preferred embodiment of the invention, and wherein:

Figure 1 is a fragmentary perspective view of a loom illustrating a practical application of this invention;

Figure 2 is a perspective view of the combined drop wire cover and warp brush embodying the features of this invention;

Figure 3 is a front elevational view of the combined drop wire cover and warp brush, with a frame part of a loom shown in cross section, and illustrating the manner in which the device of this invention is mounted on the loom and the movability of parts of the device with respect to the loom; and

Figure 4 is an end elevational view of the drop wire cover and warp brush with the longitudinal wall sections thereof shown in a partially raised position.

Referring now in detail to the drawing it will be seen that the combination drop wire cover and warp brush of this invention is in the form of an attachment to be applied to a loom without altering the structural details of the latter. To that end the device comprises a pair of attaching plates 5—5, a hood having end walls 6 that are detachably connected to the members

2

5 through the medium of hinges 7 equipped with removable hinge pins 8, and longitudinally extending walls 9, 10, respectively, hinged as at 11 and 12 to a stationary wall section 13 that extends between the end walls 6 and is secured at its opposite ends to the walls 6 at the upper edges of the latter as at 14.

The aforementioned hood comprising the walls 6, 9, 10 and 13 may be of any suitable cross sectional shape, the only requirement as to the cross sectional shape and longitudinal dimensions of the hood being that they be sufficient for the hood to extend over and substantially enclose the drop wires 15 of the loom 16 (see Figure 1) 15 to which the hood is applied as contemplated by this invention.

The wall 9 of the hood is provided at its free longitudinal edge with a flange 17 to which is secured as at 18 a brush 19. While the brush 20 may be of any suitable construction, it preferably embodies a back or base portion formed from a single suitable length of wood and into which are set bristles of a desired length and texture determined by the particular type of cloth being manufactured on the loom, it being contemplated that the bristles be of such a length and texture for effective wiping engagement with the warp to pick up all loose ends of the warp, lint, cotton or trash that might fall on the warp.

It is also within the contemplation of this invention to provide the wall 10 at its free longitudinal edge with a rolled edge 20. It may be also here stated that when desired a suitable brush may be suspended in any well-known manner from the edge 20 of wall 10 for brushing loose ends of the threads from the warp so that the loose ends will be free to fall to the floor free of the loom.

There are also suitably mounted on the wall section 13 of the hood rings or eyelets 21 which may be selectively engaged with any suitable suspension means (not shown) mounted on the loom 16 above the drop wires 15 for holding the hood in, for example, the partially raised position shown in Figure 3 to permit access to the drop wires 15, as might on occasion be required.

In applying the device of this invention to the loom 16, and as shown to advantage in Figures 1 and 3, the attaching plates 5 are secured to opposite portions of the frame 16a of the loom 16 at the desired position of vertical adjustment through the medium of tap bolts 22 that are threaded into the frame 16a and extend through slots 23 provided in the attaching plates 5. The plates 5 thus serve to support the hood of the de-

vice transversely on the loom and over the drop wires 15 which form, as is well-known in the art, part of a thread detecting mechanism or electric warp stop motion now generally constituting standard loom equipment, and the brush 19 in wiping engagement with the warp 24.

In actual practice with the hood and brush of this invention in proper position on the loom and as shown in Figure 1, the hood will effectively serve to substantially enclose the drop wires 15 to prevent lint, cotton, and other trash from falling on the drop wires, while at the same time the brush, being in wiping engagement with the warp 24, will serve to effectively pick up all loose ends of the warp and cotton and trash that would otherwise fall on the warp and, in the absence of this invention, be carried with the warp into the drop wires, or as they are sometimes referred to in the art, detectors 15.

It is well-known in the textile industry that lint, cotton and other trash which is permitted to contact the drop wires or detector fingers 15 of a loom cause what are known in the art as mat-ups, draw-backs, breakouts and other defects in the finished cloth. With my invention the causes of these defects in the cloth are prevented by reason of the fact that through the medium of the hood and brush assembly contemplated by this invention and operating in the manner herein described trash of all kinds is precluded from falling on the drop fingers or detectors 15 of the loom. As a result a loom equipped with a drop wire cover and a warp brush assembly as herein described will produce a high quality of cloth and at minimum cost, the production capacity of the loom being materially enhanced as will be apparent to those skilled in this art.

It will also be appreciated from the detailed description of this invention that either of the walls 9 and 10 may be swung upwardly on the hinges 11 and 12 so as to permit ready access to the drop wires 15 from either side of the hood; and that also by removing the hinge pin 8 of a selected hinge 7 the hood may be vertically swung upwardly on the other hinge 7 as suggested in Figure 3 so as to expose the entire assembly of drop wires 15 and thereby permit complete access to the wires.

Also by vertically adjusting the plates 5 on the frame 16a the hood and associated brush 19 are supported at the desired position of elevated adjustment with respect to the drop wires 15 and warp 24 as desired and as conditions of use may dictate.

While the invention has been described in detail in its presently preferred embodiment, it will, of course, be understood that such has been done for purposes of illustration only and not by way of limitation, and therefore only such limitations are to be imposed thereon as may reasonably come within the scope of the appended claims.

What I claim is:

1. A combination drop wire cover and warp brush for looms, comprising a casing adapted to be mounted on the loom to substantially enclose the drop wires, and a brush disposed on the casing for wiping engagement with the warp.
2. A loom attachment comprising a casing for disposition over the drop wires of the loom, and a brush mounted on the casing and extending lengthwise thereof for brushing contact with the warp and co-acting with the casing to prevent lint and other trash from falling on the drop wires.
3. A loom comprising in combination, drop wires, a casing substantially enclosing said drop wires, and a brush mounted on the said casing in brushing contact with the warp.
4. A loom comprising in combination, drop wires, a casing disposed over said drop wires, a brush mounted on the casing in wiping contact with the warp, and interengaging means on the loom and on the casing for supporting the latter and brush at selected positions of vertical adjustment on the loom.
5. A casing for disposition over the drop wires of a loom comprising attaching members, a hood having end walls hinged to the attaching members, and longitudinal wall sections hingedly supported between the end walls.
6. A casing for disposition over the drop wires of a loom comprising attaching members, a hood having end walls hinged to the attaching members, and longitudinal wall sections hingedly supported between the end walls, and a brush mounted on the free longitudinal edge of one of the longitudinal wall sections for wiping engagement with the warp.

JOHN S. DENNEY.
